US0D1104116S

(12) **United States Design Patent** (10) **Patent No.:** **US D1,104,116 S**
(45) **Date of Patent:** **** Dec. 2, 2025**

(54) **CAMERA LENS**

- (71) Applicant: **GoPro, Inc.**, San Mateo, CA (US)
- (72) Inventors: **John George Muhlenkamp, IV**, Mapleton, UT (US); **Ian Copeland Griggs**, San Francisco, CA (US); **Bessy Wen-Han Liang**, San Jose, CA (US); **Huy Phuong Nguyen**, Alpine, UT (US)
- (73) Assignee: **GoPro, Inc.**, San Mateo, CA (US)
- (**) Term: **15 Years**
- (21) Appl. No.: **29/949,373**
- (22) Filed: **Jun. 26, 2024**
- (51) LOC (15) Cl. **16-05**
- (52) U.S. Cl. USPC **D16/219**
- (58) **Field of Classification Search**
USPC D16/134, 200, 219, 237
CPC . G03B 2217/243; G03B 17/565; G03B 17/56

(57) **CLAIM**

The ornamental design for a camera lens as shown and described.

DESCRIPTION

FIG. 1 is a front, upper, right perspective view of a camera lens of our new design;

FIG. 2 is a rear, lower, left perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof; and,

FIG. 9 is a cross-sectional view thereof along line 9-9 of FIG. 7.

Broken lines of equal length (e.g., dash-dash) represent unclaimed portions of the camera housing and form no part of the claimed design.

1 Claim, 8 Drawing Sheets
